UNITED STATES PATENT OFFICE.

HARRY D. ROHMAN, OF NEW YORK, N. Y., ASSIGNOR, BY MESNE ASSIGNMENTS, TO
J. STONE & COMPANY, LIMITED, OF DEPTFORD, ENGLAND.

OUTPUT-INDICATOR.

1,286,418.

Specification of Letters Patent.

Patented Dec. 3, 1918.

Application filed December 1, 1915. Serial No. 64,456.

To all whom it may concern:

Be it known that I, HARRY D. ROHMAN, a citizen of the Republic of Switzerland, residing at New York city, county of New York, and State of New York, United States of America, have invented certain new and useful Improvements in Output-Indicators, of which the following is a specification.

This invention relates to an improvement in output indicators, and has reference primarily to an output indicator for use on dynamos of the slipping belt type, as employed in electric train lighting, heating and ventilating systems.

One of the chief objects of the invention is to provide a simple means whereby the output of a dynamo may be readily determined within practical limits, so that the belt tension may be adjusted to secure the desired dynamo output under given conditions, or to alter the output, as may be desired. My invention also contemplates the provision of an output indicator which may be readily adjusted to give correct readings, as will further appear.

The foregoing, together with such other objects as may hereinafter appear or are incident to my invention I attain by means of a construction of which I have illustrated one preferred form in the accompanying drawing, wherein—

Figure 1 is a side elevation of a dynamo showing my improvement applied thereto; Fig. 2 is a side elevation of the indicator drawn on a larger scale; and Fig. 3 is a plan view of the device of Fig. 2.

My invention will be best understood from a description of the manner in which the dynamo of a system of the character described is supported and operated. Referring particularly to Fig. 1, it will be seen that the dynamo 7 is supported from the truck or the car framing 8, as the case may be, by means of the bracket 9, and the pivotal link 10. The dynamo is driven from the axle 11 by means of the pulley 12, belt 13 and pulley 14, the pulley 14 being mounted on the shaft 15 of the dynamo. Since the link 10 is pivoted to the bracket 9, and to the dynamo, it will be clear that the dynamo, or at least part of the load of the dynamo, is carried on the belt 13. Stated in other words, the dynamo lies in the belt, the pull of the belt being primarily determined by the degree of angularity of the

dynamo. The angularity of the dynamo may be altered by the threaded rod 16 which is pivoted at one end to the link 10 and passes through the bracket 17 mounted in the framing 8.

Let us assume for purposes of illustration that the dynamo should have an output of 900 watts in order to properly supply the consuming circuits of the car to which it is attached, and also to charge the batteries, the dynamo being constructed to generate 30 ampers at 30 volts, at, let us say, 1,000 revolutions per minute. The dynamo is adjusted so that the belt 13 will slip on the pulley 14 when the desired amperage is obtained, the output thereafter remaining constant except, of course, when the speed of the train falls below a predetermined rate. The adjustment is effected through the rod 16 and link 10, the size of the pulleys and the friction of the belt also being factors to be considered in securing the desired output.

Heretofore, in this art, it has been the practice to take readings with an ammeter to find out the output of the dynamo. I propose to provide an instrument which, under given conditions, will translate within practical limits the pull of the belt into terms of output of the dynamo. Although a variety of different forms of indicating mechanism can be employed in carrying out my invention, I prefer to use an indicator A of the spirit level type, which, in order to secure a wider and more accurate range of readings, should preferably be curved. The glass 18 of the level is mounted in a suitable metal housing 19, which may be attached to any convenient part of the dynamo, as for example, the terminal block 20. The housing is fastened in position by means of studs 21, passing through slots 22 in the base 23 of the housing for a purpose which will appear. The scale on the glass is obtained from a master indicator which has been calibrated to give accurate ampere readings on standard dynamos, pulleys and belting. It will at once be seen that the indicator will give approximately correct ampere output readings for the various degrees of angularity of the dynamo; that a dynamo can be readily adjusted to give the desired output when first installed without any additional testing or readings; and that the output can from time to time be corrected or adjusted as needed.

The indicator also lends itself readily to

adjustment. This may be required in such cases as where a belt is replaced by one made of some material other than standard material, or where a pulley is replaced by one 5 of different size. Under such altered conditions, the indicator would not give correct readings, and would require readjustment, this being accomplished by loosening the screws or studs 21, and shifting the position 10 of the level. This may be done in connection with the gage device shown and described in my co-pending application, Serial No. 64,457, filed December 1, 1915. This gage device is adapted to be applied to the 15 dynamo shaft and is calibrated to give the output reading at which the belt slips. When the output has been determined by the gage, the level is shifted until the bubble is at a corresponding reading, after which the 20 screws are tightened.

While I have described my invention as applied to a constant torque dynamo of the slipping belt type, it will be understood that it is not restricted to such use, and that variations may be made without departing from the spirit of the invention.

I claim:

1. The combination of a belt-driven constant torque dynamo, means whereby the 25 dynamo is partly supported in the belt, means for adjusting the position of the dynamo to alter its load on the belt, and indicator mechanism controlled by the position of the dy-

namo for translating such position into a reading of the output of the dynamo.

2. The combination of a constant torque dynamo, means whereby the dynamo is swingingly supported, a belt for driving said dynamo, part of the load of the dynamo being carried in the belt, the point of the slip-page of the belt being determined by the angularity of the dynamo with respect to a vertical line passing through its point of support, and indicator mechanism controlled by the angular position of the dynamo for translating such position into a reading of the output of the dynamo.

3. The combination of a dynamo member, a driving member therefor, movable means for altering the driving effort of the driving member to vary the output of the dynamo, and means operated by the movement of said first means for indicating the output of the dynamo.

4. The combination of a dynamo member, a variable driving member therefor capable of exerting a driving effort sufficient to develop predetermined maximum dynamo outputs, movable means for altering the driving effort of the driving member to set a new maximum dynamo output, and means operated by the movement of said first means for indicating the output of the dynamo.

In testimony whereof I have hereunto signed my name.

HARRY D. ROHMAN.
